UNITED STATES PATENT OFFICE.

CARL WILLIAM EISENMANN, OF NEBRASKA CITY, NEBRASKA.

AUTOMATIC SWITCH.

1,250,152.

Specification of Letters Patent. Patented Dec. 18, 1917.

Application filed April 5, 1916. Serial No. 89,127.

To all whom it may concern:

Be it known that I, CARL W. EISENMANN, a subject of the Emperor of Germany, residing in Nebraska City, Otoe county, State 5 of Nebraska, have invented Automatic switches, of which the following is a specification.

My invention relates especially to automatic electric switches designed for use in 10 connection with storage battery systems, one of its objects being to provide such an arrangement of parts as will cause the main contacts of such a switch to be subjected to a relatively high voltage at the moment 15 when the switch closes, in order that any non-conducting material adhering to or formed upon these contacts and capable of being broken down by the generator voltage shall be instantly punctured and the electrical connection completed between the battery 20 and the generator when their voltages are nearly equal.

Another object of the invention is to provide an electric switch having main and auxiliary contacts, with means for certainly preventing said auxiliary contacts from continuously carrying the main current passing through the switch, in case some non-conducting or insulating material should be 30 present between the main contacts.

These objects and other advantageous ends I secure as hereinafter set forth, reference being had to the accompanying drawings, in which,

35 Figures 1 and 2 are diagrammatic representations of two slightly different switches constructed according to my invention; and

Fig. 3 is a fragmentary elevation, to some extent diagrammatic, illustrating the switch 40 contacts in the positions occupied when the switch is closed.

In the above drawings 1 represents a storage battery and 2 a generator, the former being connected to supply current to a line 45 3-4. For automatically controlling the charging of the storage battery I provide an electric switch having two pole pieces 5 and 6 between which a polarized armature 7 is mounted to oscillate. Said armature for the 50 sake of illustration is shown as having mounted upon but insulated from it a contact carrying member 8 supporting a main contact 9 and a pair of auxiliary contacts 10 and 11. Said main contact is placed so as 55 to be capable of electrically connecting a pair of main stationary contacts 12 and 13,

while the auxiliary movable contacts are designed to be capable of respectively engaging two fixed auxiliary contacts 14 and 15;— the arrangement being such that the contacts 60 10 and 11 engage said contacts 14 and 15 before and disengage them after the main contact 9 engages or disengages the contacts 12 and 13.

The contact carrying arm 8 also provides 65 a flexible or yieldable support for a third pair of contacts 16 and 17 which are insulated from it and from each other, although they are so mounted that they are capable of engaging the fixed auxiliary contacts 14 and 15. The arrangement of these two latter 70 pairs of auxiliary contacts is such that the contacts 16 and 17 respectively engage the fixed contacts 14 and 15 when the switch is open and remain in such engagement while 75 said switch is being closed until after the contacts 10 and 11 have come into engagement with said secondary contacts 14 and 15, and the contact 9 has engaged the contacts 12 and 13 when they disengage the secondary 80 contacts. Similarly when the switch is moving from its closed to its open position, the contacts 16 and 17 first come into engagement with the fixed contacts 14 and 15, the main contact 9 then disengages the contacts 85 12 and 13, and finally the contacts 10 and 11 disengage the contacts 14 and 15. The contacts 13 and 17 of this switch are connected 90 through a conductor 18 with the positive terminal of the storage battery and a magnetic winding or coil 19 mounted on the pole piece 5, is connected between this conductor and a conductor 20 leading from the positive terminal of the generator 2, being so wound 95 that it acts upon the armature 7 to hold the switch in its open position.

A second coil 21, mounted on the pole piece 6, is connected between the positive terminal of the generator 2 and a conductor 24 leading to the two contacts 12 and 16 of 100 the switch, being so wound that it acts on the armature 7 to hold the switch closed whenever current is flowing from the generator to the battery, although acting to repel said armature and open the switch when the current reverses. Also mounted on the pole piece 6 are a pair of coils 22 and 23, of which the first has one end connected to the conductor 24 and its opposite end connected through a conductor 26 and a body of resistance 25 to the negative terminal of the generator, which is directly connected to the 105 110

negative terminal of the storage battery. This coil 22 is so wound that it attracts the armature 7 when the generator voltage is greater than that of the battery, being assisted by the coil 19 under these conditions.

- 5 The coil 23 is connected between the conductor 26, leading from the coil 22 to the resistance 25 and the member 8 with the main contact 9, so that it is energized when the switch is closed at which time it is obviously connected across the line in series with the resistance 25 and manifestly serves to apply full line voltage to any non-conducting material which may lodge between the fixed and movable contacts of the switch.
- 10 Moreover this coil 23 is wound to neutralize the effect of the coil 22 so that the latter cannot oppose the action of the coil 21 in repelling the armature and opening the switch in case the charging current should reverse by reason of the generator voltage becoming lower than that of the battery.

Under normal conditions when the voltage in the storage battery is higher than that of the generator or other current source, the line 3-4 is supplied with current from the former and the switch is held open by reason of the current flowing from the storage battery through the conductor 18, coil 19 and through the generator to the negative terminal of said battery; it being noted that by reason of this energization of said coil a magnetic flux is maintained through the pole piece 5 and armature 7 which effectually keeps the latter polarized. If, however, the voltage of the storage battery falls to a predetermined point below that of the generator 2, the reversal of current flow in the coil 19 repels the armature 7, thus closing the switch. The flow of current from the generator 2 through the conductor 20, coil 21, conductor 24, switch contacts 12, 9 and 13 and conductor 18, then causes said coil 21 to hold the armature 7 in its position adjacent the pole piece 6, in which the switch is closed, so that a charging current is delivered to the storage battery. It is to be noted that when the auxiliary contacts 10 and 11 first come into engagement with the contacts 14 and 15 as the switch is being closed, the full generator voltage exists between the contacts 14 and 10 so as to instantly break down any non-conducting film or puncture any insulating substance which would interfere with their good electrical connection and which is capable of being broken down by such voltage, since through the conductor 20, coil 21, conductor 24 and contact 16, the contact 14 is connected to the positive generator terminal while the contact 10 through the cross bar 8, coil 23, conductor 26, and resistance 25 is likewise connected to the negative terminal of the generator. Thereafter in closing the switch, the main contact 9 electrically connects the

main stationary contacts 12 and 13 and finally the contacts 16 and 17 disengage the contacts 14 and 15, thus cutting off the secondary contacts 10 and 11. If therefore there should be an insulating or non-conducting body or film between the main contact 9 and the contacts 12 and 13, this similarly would be exposed to the full generator voltage as in the case of the auxiliary contacts above noted with the result that it would be instantly punctured.

70 By the above described means I insure the instantaneous electrical connection of the generator to the storage battery at the time the switch closes, thus preventing the injurious rush of current which would otherwise occur in case the insulating film or body prevented current flow between the contacts of the switch when these were first engaged and thus allowed the generator voltage to rise considerably above that of the storage battery.

75 Moreover by the use of the tertiary movable contacts 16 and 17, I effectually prevent the secondary contacts 10 and 11 from being compelled to carry the full current after the switch has been completely closed as might otherwise occur in case imperfect contact was made between the contact 9 and the fixed contacts 12 and 13;—it being understood that the mounting of the contacts 10 and 11 as well as that of the contacts 16 and 17 is preferably made of flexible or spring material which permits of the above described action of the switch, though obviously the same end might be secured by other means without departing from my invention.

80 In the system illustrated in Fig. 2 I omit the resistance 25 and the coil 23, connecting a condenser 28 between the member 8 of the switch and the negative terminals of the battery and generator. With such an arrangement of parts on closing the switch a spark is formed at the contacts due to the discharge of the condenser which thus punctures or breaks down any non-conducting material between the main contacts and secures the same result as that accomplished by the combination of Fig. 1, there being no spark at the opening of the switch. This particular form of the invention is to be preferred in some cases, since there is obviously no current flow through the condenser under operating conditions.

85 I claim:—

1. The combination of a storage battery; a generator; an electric switch for connecting the battery and generator when the former is to be charged; and means for applying substantially the full line voltage to the contacts of the switch at the time it is closed.
2. The combination of a generator; a storage battery; an electric switch for connecting said generator and battery when the lat-

ter is to be charged, and including main and auxiliary contacts; with means for puncturing any insulating material between the main contacts at the time the switch is closed.

5. 3. The combination of a generator; a storage battery; and an automatic switch for connecting the battery to the generator when the former is to be charged; with means for automatically puncturing any insulating material between the switch contacts at the moment of closing the switch to insure the instantaneous flow of current from the generator to the battery.

10 4. The combination of a generator; a storage battery; and an automatic switch for connecting the battery to the generator when the former is to be charged; with means for automatically puncturing any insulating ma-

terial between the switch contacts at the moment of closing the switch to insure the 20 instantaneous flow of a charging current; the same consisting of a branch circuit including the switch contact or contacts; with current limiting means in said circuit.

5. The combination of a conducting circuit; a generator, a storage battery, and a switch for connecting said generator to the battery when the latter is to be charged all connected in said circuit; a branch circuit connecting the movable element of the 25 switch and a part of the circuit whose voltage is greater than that of the main portion thereof; and a condenser in said branch circuit.

CARL WILLIAM EISENMAN.
